UNITED STATES PATENT OFFICE.

ROBERT C. BOECKEL, OF YORK, PENNSYLVANIA.

DESIGN FOR A BAR OF CANDY.

42,162.

Specification for Design.

Patented Feb. 13, 1912.

Application filed October 28, 1911. Serial No. 657,391. Term of patent 3½ years.

To all whom it may concern:

Be it known that I, ROBERT C. BOECKEL, a citizen of the United States, residing at York, in the county of York and State of Pennsylvania, have invented a new, original, and ornamental Design for a Bar of Candy, of which the following is a specification, reference being had to the accompanying drawing, forming part thereof.

The figure is a perspective view of a bar of candy, showing my new design.

I claim:

The ornamental design for a bar of candy, or similar article, as shown.

ROBERT C. BOECKEL.

Witnesses:

GEO. W. WILLIAMS,
R. EARL BOECKEL.
